UNITED STATES PATENT OFFICE.

WILLIAM I. BUNKER, OF LA GRANGE, ILLINOIS.

DESIGN FOR A BRACKET FOR ROCKING-CHAIRS.

SPECIFICATION forming part of Design No. 24,080, dated March 5, 1895.

Application filed December 18, 1894. Serial No. 532,264. Term of patent 7 years.

To all whom it may concern:

Be it known that I, WILLIAM I. BUNKER, of La Grange, Illinois, have invented and produced a new and original Design for Swing-
5 Brackets for Rocking-Chairs, of which the following is a specification, reference being had to the accompanying drawings, forming a part hereof.

In the accompanying drawings, Figure 1 is
10 a perspective view of my complete design; Fig. 2, a side elevation of the same; and Fig. 3 a transverse section, taken on line 3 of Fig. 1.

The leading feature of my design consists
15 in a T-shaped body portion provided with a semi-cylindrical hub slightly nearer one end of the bracket than the other.

A is the body portion of the bracket, which

is substantially U-shaped in contour and T-shaped in cross section, to form substantially 20 two right angles.

B are bearing portions by which the bracket may be fastened to a swinging chair; and C is a semi-cylindrical hub for the purpose of uniting two or more of the brackets together; 25 the whole presenting to the eye a harmonious and ornate figure, substantially the same as that illustrated in the drawings.

I claim—

The design for a swing bracket for rocking 30 chairs herein shown and described.

WILLIAM I. BUNKER.
